UNITED STATES PATENT OFFICE.

HARVEY L. HOPKINS, OF CHICAGO, ILLINOIS, ASSIGNOR OF ONE-HALF TO ARLOA B. GLADE, OF CHICAGO, ILLINOIS.

MOWING-MACHINE.

1,217,449.

Specification of Letters Patent. Patented Feb. 27, 1917.

Application filed February 25, 1914. Serial No. 820,799.

To all whom it may concern:

Be it known that I, HARVEY L. HOPKINS, a citizen of the United States, and a resident of Chicago, in the county of Cook and

5 State of Illinois, have invented certain new and useful Improvements in Mowing-Machines, of which the following is a full, clear, and exact specification.

My invention is concerned with mowing 10 machines, more especially of the rule-joint or vertical-lift type, in which the finger bar is pivoted to the main frame, or some connected portion thereof, at the shoe, so that the finger bar can be raised to a vertical 15 position, or substantially so, for transporting the machine; and it is designed to improve said machines by transferring a part of the weight of the cutting apparatus from the ground to the main axle when the team 20 is pulling the machine, thus lightening the draft by lessening the effective weight of the cutting apparatus on the ground as it is dragged thereover, and improving the traction by throwing a part of the weight 25 of the cutting apparatus on the driving wheels. My invention further contemplates utilizing the draft connections to the cutting apparatus as a medium whereby any desired portion of the weight of the pole 30 may be carried by the draft. It also contemplates an arrangement of the draft connections whereby the whiffletrees may rise and fall independently of the pole, so that they will be directly in alinement with said 35 draft connections and the points of draft at the breasts of the horses when the machine is in use.

To illustrate my invention, I annex hereto a sheet of drawings, in which the same 40 reference characters are used to designate identical parts in all the figures, of which,—

Figure 1 is a sectional view in side elevation; and

Fig. 2 is a detail of a portion of the machine as seen from the rear of the gag lever and the finger bar.

The draft wheels 10 are journaled upon the axle 11, upon which is mounted the frame 12 in any customary manner, and the 50 tongue 13 may also be connected with said

frame in any customary manner. While the driving connections for reciprocating the sickle bar 14 are illustrated, they form no part of my present invention, which is concerned more especially with the draft 55 connections. The inner shoe 15 of the finger bar 16 is pivoted to the yoke 17, which in turn is pivoted on the end 18 of the coupling frame (provided the coupling-frame type of machine is employed) in the customary 60 manner, and the tilting lever 19 may be connected by a link 20 with the arm 21 of said yoke to vary the angle at which the shoe 15 is presented to the ground over which it travels. The lifting lever 22 is pivoted at 65 23 upon the main frame or a casting carried by the tongue, and is connected by a link 24 with the inner end of the gag lever 25, which is pivoted at 26 to the horizontal bearing 27 of the yoke 17, so that the outer 70 end of the gag lever 25, coöperating with a lug 28 extending upwardly and inwardly from the shoe 15, serves to swing the outer end of the finger bar 16 upward when the lifting lever 22 is pulled back in the customary 75 manner. All the construction heretofore described may be of the ordinary type, and I have here illustrated the ordinary McCormick construction.

Pivotedly mounted upon the bolt 29, or 80 some other suitable projection extending from the side of the tongue 13, is a clevis yoke member 30, which has a yoke 31 for the whiffletrees, and an elongated vertical slot 32, through which the bolt 29 passes, so that the said clevis yoke 30 is free to rise and fall in order to keep itself in alinement with the draft connections and the points on the breasts of the horses where the draft comes. An arm 33 extending rearwardly 90 and to one side of the clevis yoke 30 coöperates with the under side of the tongue 13 to limit the rearward position to which the clevis yoke can be swung by the helically-coiled contractile spring 34, one end of 95 which is hooked into an aperture in the clevis yoke in the manner clearly shown. The other end of this spring 34 is connected to a sagging chain 35, which runs under the pulley 36 journaled in suitable bearings 100

37 formed on the upper side of the gag lever 25, and the other end of the chain is hooked on some one of the plurality of headed pins 38 extending from the arm 39 5 projecting downward from the main frame beneath the axle, as clearly shown. The clevis yoke 30 also has pivotally connected thereto a link 40, the other end of which is pivotally connected to a similar link 41, the lower end of which, in turn, is pivotally connected to an ear 42 formed on the yoke 17.

The operation of the driving connections just described is as follows: When the team is at rest with the spring under some tension, 15 the shoe 15 and the finger bar 16 have all their weight divided between the ground, the frame and the pole, the weight of the pole 13 is on the horses' necks in the customary manner. When the horses start to pull, the 20 clevis yoke 30 is swung from the full-line position of Fig. 1 to the dotted-line position, and as it swings, the spring 34 is put under increased tension, with the result that it 25 tends to straighten out the chain 35, thus lifting the power end of the gag lever 25 and causing said gag lever to act on the lug 28 of the shoe and finger bar to lift the latter, and more especially the outer end thereof. This action tends to float the weight of 30 the shoe and finger bar off the ground, and thus decrease the draft. When the pull becomes sufficient, the play in the links 40 and 41 is taken up, and the pull of the horses is 35 directly through said links onto the shoe 15, so that as much direct draft as may be necessary is possible in addition to the draft through the spring 34, which draft through the spring is, as before described, utilized in floating the finger bar.

40 It will be noted that the pull of the horses on the spring 34 and chain 35 tends to rock the main frame about the axle 11, and thus lift the outer end of the tongue 13, and if it is desired that a greater lift shall be placed 45 on the tongue, the rear end of the chain 35 can be connected to one of the lower pins 38, and it will likewise be apparent that the tension on the spring 34 can be increased as desired by shortening up the effective 50 length of the chain 35 by varying the particular link coöperating with the particular pin 38.

55 While I have shown and described my invention as embodied in the form which I at present consider best adapted to carry out its purposes, it will be understood that it is capable of modifications, and that I do not desire to be limited in the interpretation 60 of the following claims except as may be necessitated by the state of the prior art.

What I claim as new, and desire to secure by Letters Patent of the United States, is:

1. In a mowing machine, the combination

with the driving wheels, of a frame, a 65 tongue, a finger bar pivoted to the frame at its inner shoe, a gag lever coöperating with the finger bar, a roller carried by the gag lever, draft connections supported from the tongue to the finger bar, a chain attached at one end to the frame and extending beneath the roller, and a spring connecting the other end of the chain with the draft connections at the tongue.

2. In a mowing machine, the combination 75 with the driving wheels, of a frame, a tongue, a finger bar pivoted to the frame at its inner shoe, a gag lever coöperating with the finger bar, a roller carried by the gag 80 lever, a clevis yoke pivoted on the tongue, a chain attached at one end to the frame and extending beneath the roller, a spring connecting the other end of the chain with the clevis yoke, and links connecting the clevis yoke and the shoe, and taking the 85 draft when the spring is stretched sufficiently.

3. In a mowing machine, the combination 90 with the driving wheels, of a frame, a tongue, a finger bar pivoted to the frame at its inner shoe, draft connections supported from the tongue to the finger bar, a sagging chain connected at one end to the frame beneath the axle, a clevis yoke on the tongue, 95 connections between the other end of the chain and the clevis yoke so that as the chain is straightened it tends to lift the outer end of the finger bar by turning it on its pivot, and means for varying the distance from the axle to the point of attachment of said chain to vary its lift on the 100 finger bar.

4. In a mowing machine, the combination 105 with the driving wheels, of a frame, a tongue, a finger bar pivoted to the frame at its inner shoe, draft connections supported from the tongue to the finger bar, a sagging chain connected at one end to the frame beneath the axle, a clevis yoke on the tongue, 110 a spring connecting the other end of the chain and the clevis yoke, connections between the chain and finger bar so that as the chain is straightened it tends to lift the outer end of the finger bar, and means for varying the distance from the axle to the 115 point of attachment of said chain to vary its lift on the finger bar.

5. In a mowing machine, the combination 120 with the driving wheels, of a frame carried thereby, a tongue secured to the frame, a coupling frame, a yoke pivoted on the end of the coupling frame, a finger bar pivoted to the yoke, a gag lever pivoted on the yoke, a lifting lever pivoted on the tongue, connections between the lifting lever and the 125 outer end of the tongue, a clevis yoke pivoted on the tongue, pivot links connecting the clevis yoke and the first-mentioned

yoke, a pulley mounted on the gag lever, a helically-coiled contractile spring connected at one end to the clevis yoke, and a chain connecting the other end of the spring and 5 the main frame beneath the axle and passing beneath the pulley, substantially as and for the purpose described.

In witness whereof, I have hereunto set my hand and affixed my seal, this 21st day of February, A. D. 1914.

HARVEY L. HOPKINS. [L.S.]
